SHUTTLE

Filed March 19, 1932

INVENTOR,

Edward Bloom,

BY HIS ATTORNEY

John Edward.

UNITED STATES PATENT OFFICE

EDWARD BLOOM, OF PATERSON, NEW JERSEY

SHUTTLE

Application filed March 19, 1932. Serial No. 599,901.

This invention relates to that type of shuttle in which the spindle is pivoted on a transverse axis so that it may be elevated in order to replace the weft package when exhausted. Usually the spindle is pivoted on one pin and has its pivotal movement limited by another pin, and a rebent plate spring, acting on the spindle, is supported by two other pins, all four pins penetrating the 10 sides of the shuttle body. In consequence these pins not only work out and cause serious damage to the warp but they give rise to splitting of the shuttle body.

One object of the present invention is to 15 eliminate these several pins and avoid the faults to which they give rise. Another object is to provide a wound-package-supporting assembly comprising, with a housing having a pivot-affording means, a spindle 20 pivoted in said housing and which assembly shall be removably secured in the shuttle body in a simply effected and secure manner.

In the drawing,

Fig. 1 is a plan of a shuttle embodying 25 this invention;

Fig. 2 is a longitudinal substantially central vertical section thereof, with the spindle in side elevation;

Fig. 3 shows the spindle and its mounting 30 in side elevation;

Fig. 4 is a section on line 4-4, Fig. 2;

Fig. 5 is a section on line 5-5, Fig. 3; and

Fig. 6 shows the blank from which the housing portion of the mounting is formed, this 35 view being on a smaller scale.

The shuttle body 1 has the usual cavity 2 for the wound package, the same at one end terminating in a reduced extension 2a provided with a bottom and two top overhangs 40 or top flanges 2b and which I therefore term a mortise; the outer end of this mortise is preferably inclined (Fig. 2).

The spindle mounting is formed as follows: 45 3 is a housing for the spindle butt formed from the blank shown in Fig. 6 which is a piece of sheet metal having two lateral wings 3a that are bent up perpendicular to its mid-portion 3b and an end portion 3c that is bent up obliquely to meet the adjoining oblique 50 edges of such wings; the housing thus has two

side upstanding plates or walls formed by the wings and an end wall formed by the end portion 3c. At opposite points the plates have holes 4 and in a horizontal plane they also have other non-opposed recesses or holes 5. Wall 3c also has a hole 6. The holes 4 receive a pivot pin 11, to be referred to; if desired the ends of this pin may be upset or riveted to prevent it from endwise displacement, although when the mounting is in place in the mortise the sides of the latter will prevent it from such displacement. When the mounting is in place in the mortise it is held therein by a screw 7 driven through its hole 6 into the wood of the shuttle body. 60

The fixed structure of the shuttle may be regarded as comprising the body 1 and mounting, the cavity 2 extending into the mounting when the latter is in place.

The spindle is here formed in three parts— 70 the spindle proper 8, the butt 9 into which the spindle proper is screwed, and a lock-nut 10 screwed on the threaded end of the spindle and jammed against the butt. If the spindle proper becomes deformed it may thus 75 be readily removed for straightening. The butt 9 is a block fitting snugly between the plates 3a of the housing and having bottom faces 9a and 9b adapted to bear against the bottom of the housing to limit the depressing and elevating movements, respectively, of the spindle. It has a hole 9c to receive the mentioned pivot pin 11. Registering with the holes 5 of the housing when the spindle is depressed the butt also has two trans- 80 verse bores 12; these are open toward the respective plates 3a but at their other ends they are closed. Each bore contains a plunger 13 and a spring 14, the latter holding the plunger 85 against the corresponding plate. Each plunger is here a ball and therefore presents a rounded surface to the corresponding plate, the diameter of which surface exceeds that of the corresponding recess 5 with which it is adapted to engage as shown in Fig. 5. The recesses 5 may be chamfered as shown in said figure. The rounding of the surface of each plunger or/and the chamfering of the hole 5 permits the plunger to be cammed out of engagement with the hole when the spindle is 90

95 100

purposely elevated, manually. The elevation of the spindle is limited, by contact of its butt face 9b with the bottom of the housing, so that the plungers may not escape unless the pin 11 has first been removed. One plunger would serve but two, disaligned with each other, are preferred so that adequate spring power may be had within the narrow limit afforded by the butt.

- 10 10 By my construction no part of the mounting for the spindle is capable of becoming detached and falling away from the shuttle. The only element that is not positively confined is 7, but since this is a screw driven into 15 the wood of the body it is not likely to start to work out, and even if it should such would be noted by the weaver or loom-fixer before the screw became entirely free. The plungers and springs are permanently confined by the flanking portions of the fixed shuttle structure so long as the mounting is in the shuttle because they are never freed except when the pivot 11 has been removed and movement of the spindle beyond the limits normally afforded by the contact of one or the other of the butt faces 9a and 9b with the bottom of the housing is then possible.

Having thus fully described my invention what I claim is:

- 20 1. In combination, the fixed shuttle structure having an open-top cavity, a spindle having a butt arranged between sides of the cavity and pivoted in the fixed structure on an axis penetrating said sides, said butt having a bore substantially parallel with the pivot and open laterally of the butt, and a spring-pressed plunger in the bore held in contact with one side of the cavity.
- 25 2. In combination, the fixed shuttle structure having an open-top cavity, a spindle having a butt arranged between sides of the cavity and pivoted in the fixed structure on an axis penetrating said sides, said butt having a bore substantially parallel with the pivot and open laterally of the butt, and a spring-pressed plunger in the bore held in contact with one side of the cavity, said side of the cavity having a recess to receive the plunger when the spindle is depressed.
- 30 3. In combination, the fixed shuttle structure having an open-top cavity, a spindle having a butt arranged between sides of the cavity and pivoted in the fixed structure on an axis penetrating said sides and having its pivotal movement in each direction limited by said structure, said butt having a bore substantially parallel with the pivot and open laterally of the butt and always opposed by one side of the cavity in such limited pivotal movement of the spindle, and a spring-pressed plunger in the bore held in contact with said side of the cavity.
- 35 4. In combination, the fixed shuttle structure having an open-top cavity, a spindle having a butt arranged between sides of the

cavity and pivoted in the fixed structure on an axis penetrating said sides, said butt having a bore substantially parallel with the pivot and open laterally of the butt, and a spring-pressed plunger in the bore held in contact with one side of the cavity, said side of the cavity having a recess to receive the plunger when the spindle is depressed, and said plunger and recess being formed the one with a camming surface to cam the plunger out of the recess when the spindle is elevated from its depressed position.

5. In combination, the fixed shuttle structure having an open-top cavity, a spindle having a butt arranged between sides of the cavity and pivoted in the fixed structure on an axis penetrating said sides, said butt having disaligned bores substantially parallel with the pivot and open at opposite sides of the butt, and spring-pressed plungers arranged in said bores and held in contact with the respective sides of the cavity.

6. In combination, a shuttle body having a cavity, a wound-package-supporting assembly comprising, with a housing in the cavity having two spaced side walls, a spindle, said housing having means on which the spindle is pivoted between said walls to move around an axis penetrating them and means, independent of the first means, for securing the housing in the cavity, said housing and spindle having disconnection means yieldingly holding the spindle in one of the positions to which it is pivotally movable.

In testimony whereof I affix my signature.
EDWARD BLOOM.
